UNITED STATES PATENT OFFICE.

SARA WEBER McCORMICK AND HUGH MALCOLM McCORMICK, OF MORENCI, MICHIGAN;
SAID SARA WEBER McCORMICK ASSIGNOR TO SAID HUGH MALCOLM McCORMICK.

UPLIFT BELT FOR USE WITH GIRDLES AND CORSET-BRASSIÈRE COMBINATIONS.

Application filed October 21, 1927. Serial No. 227,719.

Our invention relates to support and reduction of that portion of the human abdomen located within the pelvic-cavity, by means of leverage, and is adaptable for use 5 by both men and women, but its principal purpose is to provide women with mechanically correct, efficient, comfortable and healthful abdominal support (and abdominal reduction also, when desired) in conditions 10 of abdominal ptosis; and to provide patient, physician and nurse with a long needed type of abdominal supporter in post-laparotomy and post-parturition cases.

Since March, 1903, we have devoted much 15 time and effort to experimenting, discovering and inventing means for intra-pelvically supporting and reducing the human abdomen by leverage, and the progress of our inventions is shown by United States 20 Letters Patents, Numbers—869,797, October 29, 1907; 930,217, August 3, 1909; 1,006,862, October 24, 1911; 1,006,863, October 24, 1911; 1,006,888, October 24, 1911; 1,190,250, July 4, 1916; 1,221,811, April 3, 1917; and 1,473, 25 241, November 6, 1923.

We illustrate our present invention as follows:

Figure 1 shows an ordinary corset-brassière-combination, on the person, provided 30 with uplift belts;

Figure 2 shows an ordinary girdle, provided with uplift belts;

Figure 3 shows our support-emphasis-plate;

Figure 4 shows a skeletal female pelvis, and the approximate relation of a pair of 35 our support-emphasis-plates thereto.

The fundamental distinction between ordinary-type foundation, and uplift belt 40 garments is mechanical. The former compress to achieve a desired contour of person, the latter are primarily concerned to secure efficient and healthful intra-pelvic control of the abdomen. The resultant style appearance may be identical externally, but the mechanics employed are basically unlike.

Leverage requires two fundamentals, a base as fulcrum at one end, and appropriate 45 freedom of action at the other. As uplift belts are true levers it follows that their unattached ends should operate without extraneous interference. In fact, they require nothing but themselves to operate efficiently. Hose supporters or anything else calculated

to interfere with their independent operation 55 should never be attached to them.

Our patents of April 3, 1917, and November 6, 1923, show and describe our method of designing uplift belts for and applying the same to corsets. Such designing and application are usable for uplift belts for 60 girdles and corset-brassière-combinations, subject, however, to essential calculation changes hereinafter set forth.

Apparently dependable average uplift 65 belt lower front corner depths for girdles and corset-brassière-combinations are substantially as follows:

Commencing at the waistline at the front center of the girdle or corset-brassière-combination, measure diagonally downward to a point two inches outside front center, a distance of $8\frac{3}{4}$ inches for size 32; and, similarly, for sizes 33 and 34, 9 inches; sizes 35 and 36, $9\frac{1}{4}$ inches; sizes 37 and 38, $9\frac{1}{2}$ 70 inches; sizes 39 and 40, $9\frac{3}{4}$ inches; sizes 41 and 42, 10 inches; sizes 43 and 44, $10\frac{1}{4}$ inches; sizes 45 and 46, $10\frac{1}{2}$ inches; sizes 47 and 48, $10\frac{3}{4}$ inches; sizes 49 and 50, 11 75 inches; sizes 51 and 52, $11\frac{1}{4}$ inches; sizes 53 80 and 54, $11\frac{1}{2}$ inches.

Comparison of the depths of the foregoing 23 sizes with those of the 19 sizes given in United States Letters Patent Number 1,473, 85 241, November 6, 1923, page 2, lines 5 to 13 inclusive, shows material difference throughout. As a matter of fact the new calculations are as much the product of new discovery as the old, since girdles and corset-brassière-combinations presented mechanical 90 problems with respect to uplift belts non-existent in corsets.

While the lateral dimensions of women's 95 pelvises vary more or less, a diameter of nine inches between the anterior superior spines of the ilium may be taken as an average, with the anterior superior spines of the ilium four to four and one half inches above the pubes, and the ovaries situated three to three and one half inches above the latter. The 100 average antero-posterior diameter, from sacro-vertebral angle to symphysis pubis, is four and three-quarters inches. At the back is situated the rectum, in front the bladder, and between them the vagina and uterus. 105 Undue compression, depression, or congestion of these organs, within their restricted basin, is a common cause of ill-health in

women, and an astounding number and variety of efforts have been made, for centuries, to relieve and cure such conditions.

Mechanically correct and efficient suspension of the aforesaid organs by means of comforting and helpful intra-pelvic leverage is an obvious good, and the importance of rightly positioning uplift belts equally apparent. If the bottom front corners of uplift belts are too low a woman cannot seat herself; if they are too high the base of the abdominal wall will protrude between the uplift belts and os pubis, causing much discomfort, when not actually endangering health or life.

Another mechanical factor in corsets is lacking in girdles and corset-brassière-combinations. Corsets, whether back or front laced, have semi-rigid reenforcements on their front edges, and these supplement the control of the abdomen above the uplift belt stiffener-plates shown in United States Letters Patent No. 1,190,250, July 4, 1916. Flexible girdles and corset-brassière-combinations do not have such reenforcements, and, moreover, their front meeting edges are often considerably either left or right of the front center of the trunk. Lack of supplemental control, therefore, calls for heightened uplift belts, and for extended and specific intra-pelvic abdominal support by means of an enlarged and different-shape stiffener-plate, more correctly named "support-emphasis-plate".

The maximum lateral width of the lobe of the stiffener-plate shown in United States Letters Patent No. 1,190,250, July 4, 1916, is one and seven-eighths inches, and this stiffener-plate has proved singularly satisfactory for supplying effective intra-pelvic abdominal support immediately above the symphysis pubis, but its effectiveness higher in the widened pelvis is negatived by reason of its narrow upper portion. Our present support-emphasis-plate overcomes this defect by retaining the exact size and shape of the original lobe, increasing the vertical length of the plate from four-and-one-half inches to an average of five inches, and broadening the upper portion into a second lobe having a lateral diameter of two-and-one-half inches to three-and-one-quarter inches, with two-and-three-quarters inches as a safe average. The support-emphasis-plate is preferably made of a ductile non-corrosive metal, such as aluminum, of about twenty-two gage thickness. In use, wearers

can bend our support-emphasis-plates to comfortably complement abdominal convexities. Holes for hooks or eyelets are provided for lacing.

We are pioneers in one field. Our contribution to the theory of abdominal support has been and is leverage, applied intra-pelvically, and our inventions have been and are various means for accomplishing results. The nature of our work, affected by changing modes of dress producing changing mechanical relations, is peculiarly difficult to demonstrate as invention, yet we must both discover and invent to obtain results. We began work upon part of the subject matter shown herein in February, 1911, when we made a crude uplift belt girdle. Lacking the information contained in this specification we could not reproduce in quantity or variety correctly.

Referring to drawing: Figure 1 shows corset-brassière-combination A on a woman, open, disclosing uplift belts, E, E, in position on the body, with support-emphasis-plates C, C, outlined on fronts of uplift belts. Figure 2 shows girdle B, and uplift belts, E, E, combined. Figure 3 shows support-emphasis-plate, C. Figure 4 shows support-emphasis-plates C, C, in approximate relation to a pelvis.

Uplift belts are preferably attached to girdles and corset-brassière-combinations midway between the center of the back and the side of the wearer with their upper rear corners at or about the waistline and their rear edges thence descending to lower rear corners well below the convexities of the hips.

Having shown and described our invention, we claim:

In a device of the type set forth, an outer body encircling girdle-like member or the like, having free front ends, an uplift belt secured to the rear portion of said member and having front ends, a plate carried by each of the free front ends of the belt, each of said plates being formed with a rearwardly extending lobular portion adjacent its upper end, said front ends of the belts being completely free, and means connecting the free front ends of the belt whereby the latter may be rigidly secured relative to each other for assisting intra-pelvic abdominal support.

SARA WEBER McCORMICK.
HUGH MALCOLM McCORMICK.
